UNITED STATES PATENT OFFICE.

NOEL DUPUIS, OF OLYMPIA, WASHINGTON.

BOOKBINDER.

1,330,852.

Specification of Letters Patent. Patented Feb. 17, 1920.

Application filed November 17, 1919. Serial No. 338,414.

To all whom it may concern:

Be it known that I, NOEL DUPUIS, a citizen of the United States, residing at Olympia, in the county of Thurston and State of Washington, have invented a new and useful Bookbinder, of which the following is a specification.

The device forming the subject matter of this application is a protector for the binding of a book, and one object of the invention is to provide a structure of the sort alluded to which may be adapted readily to books of different sizes. Another object of the invention is to provide novel means for holding the device on a book. A further object of the invention is to provide novel means for holding the structure at a predetermined length, so that the book engaging elements may be effective.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in end elevation, a device constructed in accordance with the invention; Fig. 2 is a transverse section; Fig. 3 is a side elevation of the protector, the line 2—2, in Fig. 3 indicating the cutting plane on which Fig. 2 is taken; and Fig. 4 shows in perspective, a book to which the device forming the subject matter of this application has been applied.

In carrying out the invention there is provided an outer trough shaped member 6 and an inner trough shaped member 7, each having an outer end wall 9 provided with pins or projections 10 extending parallel to the members 6 and 7, the pins constituting book engaging elements. The longitudinal edges of the outer trough shaped member 6 are

turned over to form guides 8, the longitudinal edges of the inner trough shaped member 7 being turned over to form reinforcements 15 slidably received in the guides 8. 55 The trough shaped member 6 is provided with a slot 11 in which operates a cam lever 12 adapted to bear against the inner trough shaped member 7. The numeral 16 denotes any suitable means for pivotally mounting 60 the cam lever 12 intermediate its ends on the outer trough shaped member 6.

In practical operation, the structure is elongated and then shortened, the pins 10 being engaged between the leaves of a book 65 5, or being engaged with some other part of the book, adjacent to the binding thereof. The cam lever 12 may be manipulated to prevent relative sliding movement between the members 6 and 7, and, thus, since the 70 device cannot elongate, the pins 10 remain engaged with the book.

Having thus described the invention, what is claimed is:—

1. A protector for the binding of a book, 75 comprising a pair of trough shaped members having end walls, the members being slidably interengaged for longitudinal adjustment; means for holding said members releasably against sliding movement; and 80 projections carried by the end walls and disposed approximately parallel to said members.

2. A protector for the binding of a book, comprising inner and outer trough shaped 85 members, the outer member being provided along its longitudinal edges with guides, and the longitudinal edges of the inner member being slidably received within the guides, the said members having end walls; 90 projections carried by the end walls and disposed substantially parallel to the said members; and a cam lever fulcrumed on the outer member and engaging the inner member.

In testimony that I claim the foregoing as my own, I have hereto affixed my signature in the presence of two witnesses.

NOEL DUPUIS.
